TURN SIGNAL INDICATOR SWITCH
Alfred R. Scheid, Charlevoix, Mich., assignor to Boyne Products, Inc., Boyne City, Mich., a corporation of Michigan

Filed Mar. 31, 1958, Ser. No. 725,246
7 Claims. (Cl. 200—16)

The present invention relates to a new and improved switch construction and more particularly to a switch peculiarly adapted to use as a control means for electrical turn indicator equipment on conventional automobiles. Still more specifically the present switch incorporates simplified operational structure to the end of eliminating numerous elements while substantially extending the operating life thereof.

Turn indicator switches are variously mounted association with varying specific types of cancelling mechanism. The driver manually or automatically selects a direction of turn and the associated mechanism moves the switch into such a selected position so as to signal the desired turn. This signalling through the switch and energizing of selected electrical circuits requires that the switch system not interfere with other signalling circuits for operating brake signal lights and the like. The switch upon completion of the turn must recycle to a selected neutral or centered position where it must remain until further selected movement. The switch must be simple, durable, and have good test life.

Most of the prior art switches known have utilized a spring centered or biased actuator member which was in sliding contact with selected conducting surfaces. The gapping between the conducting surfaces established the operational sequencing of the switch as the actuator was moved in one or another direction. Spring loaded arrangements in the manner of detent contact have also been used where the actuator moves either linearly or along and through a curvilinear path. The known types of switches required complicated actuator members, numerous parts, and elaborate insulation provisions making the switch bulky and difficult to assemble.

The switch arrangements, to accomplish these several functions simultaneously, were necessarily complex. With complexity as to structure comes attendant mechanical and electrical failure.

In view of the foregoing problems existing in the switch field and more particularly in the field of turn indicator devices, the present invention has for one of its objects an improvement of automotive turn indicator switches by way of simplification of structure.

Another object is to provide a new and improved arrangement of contactor posts.

Another object is to provide flat spring contactor elements which pocket and guide resilient bias elements so as to eliminate insulation problems as to such resilient bias elements while confining any deformation in the resilient bias members.

Still another object is to provide a case enclosure for switch elements which contains bias-to-center mechanism and resilient flat spring slide contactors without special insulation provisions.

Still another object is to extend a single lead post to accommodate a pair of simple selective contact points, thereby simplifying wiring to automotive circuits.

Another object is the provision of improved switch means wherein the inherent resilient character of the moving contactors assures adequate guiding and contact pressure, thereby reducing arcing at the contacts and reducing voltage drop through the switch.

Other objects will be more apparent to those skilled

2

in the art from the appended claims and the accompanying drawing, wherein:

FIGURE 1 is a perspective view showing the external appearance of the switch of the present invention and showing depending electrical leads.

FIGURE 2 is an exploded front elevation view of the switch shown in FIGURE 1 and exposing all of the parts thereof.

FIGURE 3 is a top plan view of the switch shown in FIGURE 1 with the cover element and actuator arm removed.

FIGURE 4 is a section view taken on the line IV—IV of FIGURE 3.

FIGURE 5 is a section view taken on the line V—V of FIGURE 3 and indicating the spring guide groove located in the recess and showing in cross section the cover in raised position with its spring retaining groove.

FIGURE 6 is a plan view of a modified form of contact.

20 In general, a recessed case is provided, the case being made of selected, mechanically durable plastic having good electrical insulating properties such as nylon or the like. The recess in the case provides a guideway or path in which flat spring contactors can linearly move. 25 On one side of the path are located a plurality of spaced apart contact posts which extend upwardly through the case and partially extend into the recess.

One other contactor post is provided through the case but does not extend into the recess. To this latter post is attached a conducting flat spring spanning element which generally parallels the path defined in the case by the recess, the ends of the spanning element being curled and bent to extend resiliently into the path at either end of the path and on the side of the case opposite the first mentioned plurality of posts. An abutment provides support for the flat spring spanning element. The abutment is integrally formed from the case material and provides a centrally located non-conducting shoulder in one side of the path.

30 40 A stop or stop pin is centrally located in the recess opposite the abutment and provides stop means at center on the other side of the path.

As one or the other of the flat spring contactor elements is selectively moved, various ones of the contactor 45 posts are resiliently contacted and when the selecting bias is removed the contactor elements return to center and rest against the shoulder on one side of the case recessed path and the stop pin on the other side of the case recessed path. In this normal centered position selected others of the contact posts are conductively bridged.

50 55 The switch case is closed by a cover which closes the recess or pathway. The bias means are simple coil springs normally biasing the flat spring contactors against the insulated stop pin and shoulder. They act against the ends of the case at one end and the flat spring contactor elements at the other end. Force to overcome the bias is applied to the contactors by means of an arm which extends through the cover and into the path of the recess between the contactors. The cover is slotted to permit lineal movement of the arm paralleling the recess pathway.

60 65 70 Each of the contact posts is attached to a lead wire. The lead wires extend from the case to connect with selected circuits. In use as an automotive directional turn indicator switch the leads permit uninterrupted operation of the brake lights with selected energization of the right and left turn indicator lights. A center notched extension from one side of the case accommodates guide control over operating and cancelling mechanism not a part of the present invention. The

switch described vastly simplifies switches such as are used in automotive directional turn indicator systems and as a consequence of this simplicity has resulted in an extension of trouble-free switch life with attendant production economies.

Referring more specifically to the drawing, the assembled switch 11 is shown in FIGURE 1. The switch 11 comprises a case 12, a cover 13, an actuating arm 14 extending through the cover 13, a pair of resilient, flat spring contactor members 15 and 16, a pair of coil springs 17 and 18, and a flat spring span contact 19. Imbedded in the case 12 are fixed in line contact posts 20, 21, 22, 23, and 24 viewing the posts in the light of FIGURE 3 from left to right. In FIGURE 2 the parts are exploded to indicate their simplicity. FIGURE 2 also demonstrates the extreme ease of assembling the switch 11. A contact post 25, retaining the span contact 19, is also imbedded in the case 12 opposite the post 22. Leads 26, 27, 28, 29, 30, and 31 are secured to the posts 26, 21, 22, 23, 24, and 25 respectively and extend to properly join, for example, an automobile wiring harness.

The case 12, cover 13, and arm 14 are made of non-conducting or insulating material. The contact posts 29, 21, 22, 23, 24, and 25 are cast or molded in place in the case 12 and are of conducting metallic material. The span contact 19 and the flat spring contactor members 15 and 16 are also formed of conducting material. The coil springs 17 and 18 are of metal material but, as will be seen, cannot short circuit selected circuits within the switch case 12.

The case 12 is provided with an elongate rectangular recess 32 which provides a path for substantially the length of the case 12. A shallow step 33 defines the width of the path 32 and the length is defined by the end walls 34 and 35 of the case 12. Mounting ears 36 and 37 extend from the case 12 to provide switch mounting means. A center notched extension 38 of the case 12 protrudes upwardly from one side of the case 12, "upwardly" being with reference to the showing of the case 12 in FIGURE 2. The rectangular cover 13 is provided with an external guideway 39. The cover 13 defines a slot or opening 40 therethrough for substantially the length of the guideway 39 which parallels the recess 32 in the case 12 when the cover 13 is in position. On assembly the cover 13 rests on the step 33 of the case 12.

Spaced along one side of the recess 32 are the imbedded posts 20, 21, 22, 23, and 24, the posts extending into the recess 32. The centermost post 22 is supported by a stop pin 42 which rises from the floor of the recess 32 and is adjacent and parallel with the post 22. The pin 42 is an integral extension of the case 12. Opposite the recess 32 from the pin 42 is an abutment 43 which extends into the pathway established by the recess 32. Imbedded in the recess abutment 43 of the case 12, and therefore insulated from the recess 32, is the post 25. The post 25 is identical to the posts 20, 21, 22, 23, and 24 on the opposite side of the recess 32 except that it is in secure contact and holding relationship to the spanning flat spring element 19. The spanning element 19 extends for substantially the length of the case 12 and is provided with resilient curled ends 44 and 45 which extend into the recess 32 substantially opposite the contact posts 20 and 24 respectively. The element 19 is retained in a channel 43a through the abutment 43. The channel 43a is provided with spring clips 43b which act against the flat portion of spanning element 19 to assure simple assembly but good contact with the post 25. The clips 43b are actually extensions of the case 12 partially into the channel 43a to spring the spanning member 19 into contact with the post 25.

The pair of flat spring moving contactors 15 and 16 (FIGURES 2-4 are identical but oppositely positioned resilient members in guiding contact with the walls of the recess 32 as defined by the step 33 and make conducting resilient contact with selected of the spaced apart posts.

Pockets 48 and 49 are provided in the contactors 15 and 16 respectively, being bent into the flat spring forming the contactors 15 and 16 as best shown in FIGURE 3. These pockets 48 and 49 retain one end of the coil springs 17 and 18 respectively. The general configuration of the contactors 15 and 16 may be likened to the letter W with an exaggerated undulation at the center forming the pockets 48 and 49 respectively. The terminal ends of the contactors 15 and 16 are curved to ride over any obstacles in the pathway 32. Since the contactors 15 and 16 are of substantially the width of the recess 32 depth, the contactors are capable of sliding in the recess 32, while being in resilient contact at all times with the step 33 and necessarily at least one of the posts in whatever position the contactors 15 and 16 may be selected to take. The transverse resilience of the contactors 15 and 16 in the pathway 32 is by reason of the spring-like configuration of the contactors 15 and 16.

The coil springs 17 and 18, as shown in FIGURE 3, bias the contactors 15 and 16 into a normal position against the stop pin 42 and abutment 43 with closed contact as between posts 21 and 22 on one side and posts 22 and 23 on the other side. The bias is accomplished by the springs 17 and 18 bearing in compressed relationship upon the ends 34 and 35, respectively, of the case 12 and against the pockets 48 and 49 of the contactors 15 and 16.

An alternative form of contactor is shown in FIGURE 6 as comprising essentially a U-shaped conductor 16' which may be in pairs in lieu of the elements 15 and 16.

The actuating arm 14, having a guide flange 50 to guideingly mate with the guideway 39 in the cover 13, includes a part 14a that extends through the cover slot 40 and into the recess 32 between the contactors 15 and 16. Movement of the arm 14 in its fixed lineal pathway selectively moves one or the other of the contactors 15 and 16 against the corresponding coil spring bias. The contactor thus moves, always in contact with at least one post, into selected other engagement with others of the posts. In the extreme of travel, for example, the contactor 15 is moved to ultimately engage posts 20 and 21 on one side of the recess 32 and one curled end 44 of the spanner bar element 19. The other contactor 16 remains biased against the posts 22 and 23. Upon release of the arm moving force acting upon arm 14, the spring 17 returns the contactor 15 to its normal position. This "cancelling" effect is achieved by apparatus not a part of the present invention but is assisted by the cam action achieved by the notched extension 38 extending from the case 12.

Assembly of the switch is quite simple as may be seen by reference to FIGURE 2. The leads 26, 27, 28, 29, 30, and 31 are cast or molded in place with the posts 20, 21, 22, 23, 24 and 25 respectively, or are crimped or otherwise fixed to the posts after the casting or molding of the insulated body or case 12. Best results have been achieved using dimensionally accurate injection molding. The flat spring contactors 15 and 16 are pressed into place in the recess 32 and the coil springs 17 and 18 are positioned in the recess 32 pocketed by the contactors 15 and 16 and nested in the groove 41 in the bottom 46 of the case 12. This biases the contactors 15 and 16 into the neutral or centered normal position. The spanning element 19 is sprung into position in the channel 43a, its ends 44 and 45 providing extension contacts from the post 25, which resilient ends 44 and 45 extend into the pathway established by the recess 32.

The cover 13 is closed on the case 12 to rest on the step 33 and the actuator part 14a is inserted through the slot 40 and between the contactors 15 and 16. The groove 41 in the cover 13 maintains the deformation in the springs 17 and 18. The arm 14 is movable along the guideway 39 maintained against distortion by the flange 50. The slot 40 limits the travel of the arm 14.

In operation the switch 11 is securely located adjacent 75 suitable connecting and cancelling linkage. The driver

of an automobile, for example, manually selects a left or right turn and moves a toggle arm. The toggle overcomes the bias of spring 17 or 18 and moves the actuating arm 14 to the left or right selectively and moves with it one or the other of the contactors 15 or 16. The movement of this contactor does not disturb a fixed closed circuit maintained by the undisturbed contactor as between two posts, but does select and energize an indicator circuit with the moved contactor. This overcoming of the switch bias is held by apparatus not a part of this invention until the turn is complete. The lever or toggle is then disengaged and the switch bias returns the selected contact back to center or normal position ready for another selected actuation.

The switch arrangement thus described is exceedingly simplified over known switches for a similar purpose. A minimum number of parts is required and minimum deformation of contactor members is involved. The coil springs do not require special insulating provisions since they are adequately maintained against deformation by the pocketing by the contactor members and the insulating housing. Testing of the device by repetitive cycling has shown its ruggedness and long life. Operational usage to date indicates low cost by reason of simplification of structure and assembly.

Having thus described my invention it will be appreciated that many modifications within the skill of the art are possible and such modifications are intended to be included limited only by the scope of the hereinafter appended claims.

What I claim is:

1. In an electrical plural contact center biased switch, the combination comprising: a case of insulating material defining a longitudinal stepped recess; a plurality of in-line spaced apart contactor posts through and into said case and extending into the path created by the longitudinal recess in said case on one side only; a stop extending upward from said case and adjacent to the centermost of said posts; an abutment extending from said case and providing stop means opposite from said stop; a conducting bar substantially paralleling said longitudinal recess and insulated therefrom by said case and having resilient tips extending into said recess near the outer extremes thereof; a pair of flat spring conducting elements resiliently spanning said recess and bent to form pockets at their center with guide-like surfaces engaging the sides of said recess; a pair of resilient members acting longitudinally in said recess against the pockets of said flat spring conducting elements normally urging said conducting elements into centered relationship against said stop and abutment and in closed contact with at least three of said in-line contactor posts; and actuator means selectively movable along the path established by the said recess and moving one or the other of said conducting flat springs to close electrical contact with selected other of said posts and said conducting bar.

2. A switch construction comprising a case formed of insulating material and having a longitudinally extending recess therein; a plurality of spaced apart contacts supported by said case and extending into said recess; a pair of independent conducting elements each of which is slideably mounted in said recess for independent movement from a first position in which it engages selected ones of said contacts to another position in which it engages selected others of said contacts, each of said conducting elements being bent to form a pocket extending longitudinally of said recess; actuator means slideably supported by said case and having a part extending into said recess between said conducting elements; and resilient means in said recess seated in the pockets of said conducting elements and reacting between said case and said pair of conducting elements and urging the latter towards said part, said part, said conducting elements, said resilient means and said contacts all being located at substantially the same level within said case.

3. The construction set forth in claim 2 wherein said case includes abutments extending into said recess intermediate its ends and against which corresponding portions of said conducting elements seat when the latter are in their said first positions.

4. A switch construction comprising a case formed of insulating material, said case having side and end walls forming a longitudinally extending recess; a plurality of spaced apart contacts supported by said case and extending into said recess; a pair of opposed conducting elements each of which is slideably mounted in said recess for movements from a first position adjacent the center of said recess to a second position adjacent one end of said recess, said conducting elements engaging selected contacts when in either of said positions, each of said conducting elements being bent to form a spring seat; a pair of springs mounted in said recess one adjacent each end wall thereof and reacting between its associated wall and the spring seat of the adjacent conducting element to urge the latter toward its said first position; and an actuator member slideably mounted in said recess between said conductor elements.

5. The construction set forth in claim 4 including stop means supported by said case and extending into said recess at the center thereof and against which said conductor elements abut.

6. A switch construction comprising a case formed of insulating material and having a recess therein; a plurality of spaced apart contacts supported by said case extending into and along one side of said recess; a plurality of contact elements supported by said case and extending into and along said recess at the opposite side thereof; a pair of opposed independent conducting elements each of which is slideably mounted in said recess for independent sliding movement from a first position adjacent the center of said recess to a second position at the adjacent end of the latter, each of said conducting elements being in engagement with selected ones of said contacts in one of said positions and in engagement with one of said contact elements and with selected others of said contacts in the other of said positions; an actuating member slideably supported by said case for movement from a first position adjacent the center of said recess toward either end thereof and having a part extending into said recess between said conducting elements for engagement therewith; and a pair of springs received in said recess, said springs being located one between each end of said recess and one of said conducting elements and acting on the latter to urge it and said part towards their said first positions, said conducting elements, said part and said springs all being located at substantially the same level within said case.

7. A direction signal switch construction comprising a casing formed of insulating material and having a recess therein; first terminal means in said recess between the ends thereof; second terminal means in said recess between the ends thereof; electrically conductive spanner means connected to said second terminal means and extending on opposite sides thereof into said recess; a plurality of electrical contacts supported by said casing and extending into said recess; a pair of opposed independent conducting elements in said recess on opposite sides of said first and second terminal means and mounted for sliding movement independently of one another from a first position in engagement with said first terminal means and in engagement with selected ones of said contacts, to a second position away from said first terminal means and in engagement with selected others of said contacts and with said spanner means; movable actuator means interposed between said switch members for engagement with either of the latter and movable relatively to said casing in either of two opposite directions from a neutral position for effecting movement of a selected switch member from its first position to its second position; and a pair of springs received in said recess, said

springs being located one between each end of said recess and one of said conducting elements and acting on the latter to urge it and said actuator means toward their respective first and neutral positions, said contacts, said spanner means, said switch members, said movable actuator means and said springs all being located at substantially the same level in said casing.
